UNITED STATES PATENT OFFICE

JOHN TRAIN, OF PIPESTONE, MINNESOTA

COMBINED BED AND TENT

Application filed January 5, 1927. Serial No. 159,148.

This invention relates to tents, and more particularly to a tent especially designed for tourists' use.

The primary object of the invention is to provide a combined tent and bed construction, which may be readily folded into a small and compact article to facilitate the storing thereof, due consideration being given to the structure to permit the same to be set up with facility.

Another object of the invention is to provide a tent of this character which may be set up adjacent to a motor vehicle in such a way that the motor vehicle provides the supporting structure for one side of the tent.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a perspective view of a tent frame constructed in accordance with the invention as secured to a motor vehicle structure.

Figure 2 is a plan view of the upper portion of the tent structure, the corner bars at one side thereof being shown in section.

Figure 3 is a fragmental plan view illustrating the lower portion of the structure.

Figure 4 is a sectional view taken on line 4-4 of Figure 2.

Figure 5 is a sectional view taken on line 5-5 of Figure 3.

Figure 6 is a sectional view taken on line 6-6 of Figure 2.

Figure 7 is a sectional view taken on line 7-7 of Figure 2.

Referring to the drawings in detail, the device embodies corner posts 5 and 6 respectively, which corner posts are formed preferably of angle irons, the upper ends thereof extending inwardly providing short supporting arms 7 to act as supports for the fabric covering 8, that extends over the supporting

arms and over the top of the vehicle where one edge of the covering 8 is secured along one edge of the top.

Secured to the corner post 5 and extended towards the corner post 6, is a supporting arm 9 which is held in a horizontal position by means of the brace bar 10, the supporting arm being provided with an inwardly and downwardly extended upper portion 11 adapted to fit over the side rails 12 associated therewith. A pin indicated at 13 is carried by the arm 9 and is designed to fit within an opening of the rail 12, that falls opposite thereto, when the side rails are being positioned.

The side rail 12 embodies an angle bar and is provided with an opening to receive the pin 14 of the cooperating section 15 of the side rail so that the sections will be securely held together. One end of the section 15 is fitted within inwardly and downwardly extended portions 16 of the supporting arms 17 secured to the corner post 6, to the end that the section 15 is securely held in a horizontal position.

The reference character 18 indicates the head rail of the frame, while the reference character 19 indicates the foot rail of the frame and as shown, the head rail which is constructed preferably of angle bar material has its outer end fitted over the adjacent end of the rail section 12 to support the head rail against downward movement.

The opposite end of the head rail is bolted to the bracket member 20 by means of the bolt 21, which bolt also passes through the section 22 of the inner side rail.

As shown, the bracket is of a construction to fit over the upper edge of the side of the body of a motor vehicle, the same being provided with a depending portion 23 to engage the side of the vehicle body to hold the bracket in its active position.

Associated with the bracket 20 is a bracket 24 which is provided with an opening 25 to receive the telescoping sections of the side rail to support the opposite end thereof. This side rail also embodies a section 26 that is bolted to the foot rail 19 at its end. An intermediate supporting bar 28 is provided and

is formed with end sections to accommodate the cooperating sections of the side rail.

These cooperating sections are provided with openings designed to register to accommodate a suitable securing pin whereby when the sections have been moved to their active positions as shown by Figure 2, the pin may be inserted to hold the sections against movement with respect to each other.

10 The corner post 6 is provided with a supporting arm 29 under which one end of the foot rail 19 is positioned to support the foot rail in its horizontal position, the opposite end of the foot rail being secured to the section 26. These side rails, head and foot rails act 15 as supports for the fabric material 30 which forms the upper bed or bunk.

Adjacent to the lower ends of the corner posts are inwardly extended supporting members 31 which are provided with pins 32 adapted to fit in openings formed in the sections 33 of the side rail 34. One of the sections of the side rail 34 is formed with a pin 35 adapted to fit in an opening of the adjacent section to secure the adjacent ends of the sections together and prevent movement thereof with respect to each other.

The reference character 36 indicates the head rail of the lower bed or bunk, and this rail is connected with the corner post 5, which 30 supports the same.

Cooperating with the side rail 34 is a sectional inner side rail 37, each of the sections having inwardly extended end portions 38 overlapping the adjacent section in a manner 35 to permit of sliding movement of one section with respect to the other section.

A bracket 39 has its end secured to the inner side rail section of the lower bunk, and as shown, this bracket has curved portions 40 adapted to fit over the hub cap of the adjacent rear wheel of the vehicle to which the device is applied, thereby securing the tent frame against movement at this point.

45 The foot rail indicated at 41 has connection with the corner post 6 at one of its ends, while the opposite end thereof has connection with the inner side rail. The head and foot rail of the lower bed construction support the fabric material 42 for providing the lower 50 bed.

Pivottally connected with the post 5 is an arm 43 which has its upper end extended slightly inwardly providing a support for the covering 8.

55 The reference character 45 indicates a brace rod that has connection with the upper portion 7 of the corner post 5 and has its opposite end fitted in a suitable opening formed in the arm 43 whereby the arm 43 will be held in its extended position.

From the foregoing it will be seen that due to this construction the device may be readily disassembled and made into a small and compact article for storing and transporting, but 65

one which may be readily assembled in the formation of a tourist's tent, the motor vehicle acting as one of the supporting structures.

It will also be seen that a pair of beds are provided affording sleeping accommodations.

I claim:

1. In a tent construction, brackets having hooks adapted to fit over the upper edge of a motor vehicle body, side bars fitted on the brackets, end bars connected with the side bars, corner posts connected with the end bars, and a cover fitted over the end bars and extended over a motor vehicle positioned adjacent to the device.

75 2. In a tent construction, a frame including end members and adjustable side members, corner posts to which the end members and side members are secured, brackets having hooks hooked over the upper edge of a motor vehicle body positioned adjacent to the frame, one of said brackets adapted to receive an end member and one end of one of the side members, the other bracket adapted to receive one of the side members, the upper ends of the corner posts being extended inwardly defining supports, and a cover fitted over the corner posts and inwardly extended ends of the corner posts to house the frame.

80 90 In testimony that I claim the foregoing as my own, I have hereto affixed my signature.

95 JOHN TRAIN.
